HEAT EXCHANGE APPARATUS IN
REFRIGERATION SYSTEMS

Leslie B. M. Buchanan, Springfield, Mass., assignor to Westinghouse Electric Corporation, East Pittsburgh, Pa., a corporation of Pennsylvania

Application December 29, 1943, Serial No. 516,006

5 Claims. (Cl. 62—115)

1

This invention relates to refrigerating apparatus, more particularly to refrigerating apparatus comprising a secondary refrigerant.

It is an object of the invention to provide an improved heat exchanger between the primary and the secondary refrigerating systems.

Another object of the invention is to provide an efficient heat exchanger between the primary and the secondary refrigerating systems, which heat exchanger affords ready removal of one of the systems from the other.

A further object of the invention is to provide a heat exchanger between an intermittently operated primary refrigerating system and a secondary refrigerating system, which heat exchanger refrigerates the secondary system during and for a short period after the operation of the primary system.

These and other objects are effected by the invention as will be apparent from the following description and claims taken in connection with the accompanying drawings, forming a part of this application, in which:

Fig. 1 is a sectional view of the heat exchanger of this invention taken on the line I—I of Fig. 2;

Fig. 2 is an end elevation of the heat exchanger of this invention;

Fig. 3 is a diagrammatic illustration of refrigerating apparatus including the heat exchanger shown in Figs. 1 and 2; and

Fig. 4 is a sectional view similar to Fig. 1 of a modification of a heat exchanger of this invention.

Referring specifically to the drawings, the primary refrigerating system of the apparatus comprises a compressor 10 and a motor 12 for driving the same, both the compressor 10 and the motor 12 being located in a sealed casing 14. The compressor includes an entrance port 16 communicating with the interior of the casing 14 and an exhaust port communicating through a tube 20 with the upper portion of a condenser 22. Refrigerant vapor is compressed and forced by the compressor 10 into the condenser 22 wherein it is cooled and liquefied. The condenser 22 is cooled by a current of air drawn therethrough by a fan 24 driven by a motor 26. The condensed refrigerant passes through a capillary tube 28 to a primary evaporator 30 in which a portion of the liquid refrigerant vaporizes.

The refrigerant flows from the evaporator 30 into a vessel 34 through a tube 32 connected to an upper portion of the vessel 34. The remaining liquid of the refrigerant vaporizes in this vessel 34. The vessel 34 forms a header and also a part

2

of the heat exchanger 36 of this invention. A tube 38 connects with an upper portion of the vessel 34 and conducts the vaporized refrigerant from the vessel 34 to the casing 14 for recirculation. A quantity of lubricating oil 40 is located in the casing 14 for lubricating the compressor 10 and motor 12 and for another purpose which will be described subsequently. The refrigerant in the primary system is "Freon" (dichlorodifluoromethane) which refrigerant is miscible in and has an affinity for mineral oil such as the lubricating oil 40.

The motor is energized from a source of power (not shown) through leads 42 and 44, and a thermostatically operated switch 46 is located in the lead 42. The switch 46 is controlled by a Sylphon bellows 48 which is operated by the pressure of a volatile liquid located in a bulb 50 positioned in heat exchange relationship with the evaporator 30. The vapor pressure of the volatile liquid is conducted by a tube 52 to the bellows 48. The thermostatic switch 46 causes the refrigerating apparatus consisting of the motor 10, the condenser 22, and the evaporator 30 to operate intermittently to keep the temperature of the evaporator 30 substantially constant. This intermittent operation comprises an operating cycle and a nonoperating cycle which hereafter will be referred to as the "on" cycle and the "off" cycle. The vessel 34 forms a header for the primary refrigerating system in which the liquid and the vaporized refrigerant of the system separate and also traps at least a portion of the refrigerant liquid entering it so that the portion cannot escape through either of the tubes 32 or 38 during the "off" cycle. The vessel 34 comprises a cup 54, the lateral outer surface of which is cone shaped. The edge of the cup 54 is turned outwardly to provide a flange 56, and a cover 58 is brazed to the flange 56 to seal the vessel 34.

The secondary refrigerating system includes an evaporator 60 comprising a serpentine tube 62, the ends of which communicate through tubes 64 and 66 with the upper and lower portions, respectively, of a second vessel 68 located in heat transfer relationship with the vessel 34. The vessel 68 forms another part of the heat exchanger of this invention.

The vessel 68 comprises a conical cup 70 similar in shape to the cup 54 and a cylindrical cup 72 which is fitted over the conical cup 70. The cylindrical cup 72 is provided with a flange 74 which is brazed to the flange 76 of the conical cup 70 to form a closed chamber. The vessel 68 thus comprises a re-entrant portion con-

sisting of the cup 70, the inner surface of which is in contact with the cup 54.

The cover 58 and the flanges 56, 74 and 76 are perforated at diametrically opposite sides thereof and bolts 78 are passed through the perforations of the flanges to draw the cup 54 tightly into the cup 70 and into a wedging engagement therewith to provide a good heat conducting contact. The cups 54 and 70 are preferably formed of brass or other good thermal conducting metal. The secondary system contains a volatile refrigerant. The cup 54 may be provided with internal fins 80 and the cup 70 with external fins 82 as shown in Fig. 4 to increase the heat conduction between each of the cups 54 and 70 and the respective refrigerant in contact with these cups.

Operation

The refrigerating apparatus is adapted for use in a refrigerating cabinet in which two compartments are maintained at different temperatures. One compartment is refrigerated by the primary evaporator 30 to a relatively low temperature to produce ice cubes or store frozen foods. The other compartment is cooled by the secondary evaporator 60 and is maintained at above freezing temperature for the storage of unfrozen foods.

The portion of the refrigerant liquid of the primary system which is trapped in the vessel 34 during the "on" cycle of the primary system will evaporate at least in part during the "off" cycle, a part of the refrigerant vapor passing downwardly through the tube 38 into the casing 14 where a portion of it is absorbed by the lubricating oil 40. Another portion of the vaporized refrigerant from the vessel 34 passes through the tube 32 to the relatively colder evaporator 30 and condenses therein. The evaporation of the refrigerant in the vessel 34 during the "off" cycle of the refrigerant compressor 10 cools and condenses the refrigerant vapor in the vessel 68. The condensed refrigerant runs down the tube 66 and re-evaporates in and cools the secondary evaporator 60. This action tends to continue the cooling effect of the secondary evaporator 60 during the "off" cycle of the primary system.

Applicant's refrigerating apparatus comprises a secondary system which is separable from the primary system so that each system may be manufactured separately and be separately installed in a cabinet. This is effected by the complete separability of the vessel 68 from the vessel 34. A coating of heavy machine oil is preferably placed on the outer surfaces of the cups 54 and 70 prior to their union together, which oil fills any voids between the two cups and aids in the transfer of heat.

It will be apparent from the above that this invention provides an improved heat exchanger between the primary and secondary refrigerating systems of a refrigerating apparatus. It will further be apparent that the heat exchanger affords separate manufacture of the primary and secondary refrigerating systems. It also provides for refrigerating the secondary system during the "off" periods of the primary system.

While the invention has been shown in several forms, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What is claimed is:

1. In a heat exchanger for exchanging heat between two fluids, the combination of a substantially closed vessel having a portion of its walls formed into the shape of a cone and adapted to contain a fluid in contact with said wall portion, heat-conducting fins extending from the walls of said cone into the interior of said vessel, a second substantially closed vessel adapted to contain a fluid and having walls forming a re-entrant portion nesting snugly around the cone-shaped portion of the first-named vessel, and heat-conducting fins extending from the walls of said re-entrant portion into said second vessel.

2. Refrigerating apparatus comprising a primary system including a first evaporator, a second evaporator communicating with said first evaporator and forming a header, a casing containing a compressor and lubricating oil, a tube connecting said second evaporator with said casing, a condenser receiving compressed refrigerant from said compressor, a conduit connecting said condenser with said first evaporator, a thermostat for starting and stopping said compressor, and a volatile refrigerant in said primary system, said refrigerant having an affinity for the oil in said casing, said refrigerating apparatus also including a secondary refrigerant circuit having a heat-absorbing portion and a heat-rejecting portion in intimate heat-exchange relationship with at least a portion of said second evaporator, said primary system being arranged to prevent drainage of liquid refrigerant from the heat-exchange portion of the second evaporator when said thermostat stops said compressor.

3. Refrigerating apparatus comprising a primary system including a first evaporator, a second evaporator forming a header, a passageway connecting the first and second evaporators, a casing containing a compressor and lubricating oil, a tube connecting said second evaporator with said casing, a condenser receiving compressed refrigerant from said compressor, a conduit connecting said condenser with said first evaporator, a thermostat for starting and stopping said compressor, and a volatile refrigerant having an affinity for the oil in said casing, said refrigerating apparatus also including a secondary refrigerant circuit having a heat-absorbing portion and a heat-rejecting portion in intimate heat-exchange relationship with at least a portion of said second evaporator, said primary system communicating with an upper portion of said second evaporator, said passageway of the primary system being arranged to prevent drainage of refrigerant liquid from said second evaporator to said first evaporator when said thermostat stops said compressor.

4. Refrigerating apparatus comprising a primary system including a first evaporator, a second evaporator, a passageway connecting the first and second evaporators in series, a casing containing a compressor and lubricating oil, a tube connecting said second evaporator with said casing, a condenser receiving compressed refrigerant from said compressor, a conduit connecting said condenser with said first evaporator, a thermostat for starting and stopping said compressor, and a volatile refrigerant in said primary system, said refrigerant having an affinity for the oil in said casing, said refrigerating apparatus also including a secondary refrigerant circuit

having a heat-absorbing portion and a heat-rejecting portion in intimate heat-exchange relationship with at least a portion of said second evaporator, said tube of the primary system communicating with an upper portion of said second evaporator, said passageway being arranged to prevent drainage of liquid refrigerant from said second evaporator to said first evaporator when said motor is stopped by said thermostat.

5. Refrigerating apparatus comprising a primary circuit including a first evaporator, a second evaporator forming a vessel, a passageway connecting said vessel with said first evaporator, means for supplying refrigerant liquid to said first evaporator and for withdrawing refrigerant vapor from an upper portion of said vessel, said means supplying sufficient refrigerant liquid to said first evaporator to flow through said passageway into said vessel, said means being adapted to be rendered active and inactive, said refrigerating apparatus also including a secondary refrigerating circuit having a heat-rejecting portion in

intimate heat-exchange relationship with said vessel, and a heat-absorbing portion, said passageway communicating with an upper portion of said vessel to trap refrigerant liquid in said vessel when said means is rendered inactive after a period of activity.
